(57) **CLAIM**

The ornamental design for a notebook computer with dual display screen, as shown and described.

DESCRIPTION

FIG. 1 is a perspective view of a notebook computer with dual display screen showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the notebook computer with dual display screen of FIGS. 1-7 shown in an alternate position;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view of the notebook computer with dual display screen of FIGS. 1-7 shown in another alternate position.

The dashed broken lines shown in the drawings illustrate portions of the notebook computer with dual display screen

(Continued)

that form no part of the claimed design. The dot-dash broken lines define the bounds of the claimed design and form no part thereof.

1 Claim, 12 Drawing Sheets
